WIRE STRANDING MACHINE

Albert E. Winslow, Norwich, Conn., assignor, by
mesne assignments, to Farrel-Birmingham
Company, Incorporated, Ansonia, Conn., a cor-
poration of Connecticut

Application January 11, 1944, Serial No. 517,859

17 Claims. (Cl. 57—34)

This invention relates to a machine for stranding wire and more particularly to light-weight wire or wire of a relatively small diameter.

Heretofore wire stranding has usually been accomplished in machines capable of handling relatively heavy wire. Such large machines are cumbersome and operate at a slow speed and although designed for handling heavy wire are usually also used for light wire. Although light wire cable may be made upon this type of machine I have found that such a cable can be made much more efficiently upon a lighter faster running machine.

One of the objects of this invention is to provide a lighter weight faster operating machine which will handle relatively light weight strand wires to lay them in cable formation.

Another object of this invention is to provide for the even and uniform laying of the strands of wire into a cable formation that an improved cable may be provided.

Another object of this invention is to provide stress free cable by so forming the individual wire strands that they do not tend to fly open or spread apart if the cable is severed.

Another object of this invention is to provide an arrangement whereby a broken end may be easily retrieved for re-threading of this end should the end break.

Another object of this invention is to put in two twists for each single revolution of the means for guiding and twisting the wire.

Another object of this invention is to provide a cable which will be straightened and will have any kinks therein taken out as it passes through the machine.

Another object of the invention is to provide a machine whereby the pulling stress of drawing the wire through the flexing mechanism may be provided for while permitting relaxing of the tension on the wire cable in the reeling thereof.

Another object of this invention is to provide an arrangement whereby the wire may be measured as it is formed.

A still further object of this invention is to provide an arrangement for quickly stopping the machine either upon a predetermined length having been provided and reeled or upon the breaking of one of the individual strands prior to its being laid.

With these and other objects in view, the invention consists of certain novel features of construction, as will be more fully described and particularly pointed out in the appended claims.

In the accompanying drawings:

Fig. 1 is an elevation of the machine with the

lower part of the casing removed for viewing the mechanism;

Fig. 2 illustrates in elevation the creel and rotary disc in relation thereto and in section a part of the supporting mechanism with parts omitted;

Fig. 3 is a diagrammatic view partly in section of the creel, and the leading of the various strands through the spindle, also showing the other parts 10 which operate upon the cable after the same is formed;

Fig. 4 is a sectional view on substantially line 4—4 of Fig. 2;

Fig. 5 is a fragmental view of the lower portion 15 of the creel illustrating the brake for frictioning each of the supply packages;

Fig. 6 is a sectional view of the spindle illustrating the mounting of the creel and the guide through which the various strands of wire extend to be laid;

Fig. 7 is a section on line 7—7 of Fig. 6;

Fig. 8 is a section on line 8—8 of Fig. 6;

Fig. 9 is a sectional view illustrating the drive of the main spindle from a motor and certain other drives related thereto for various mechanism of the machine;

Fig. 10 is a top plan view of the false twister mechanism and showing fragmentally the drive therefor;

Fig. 11 is a sectional view taken substantially on line 11—11 of Fig. 10;

Fig. 12 is a sectional view taken on substantially line 12—12 of Fig. 10;

Fig. 13 is a fragmental view illustrating the arrangement of the cable from the hauler to the reeling mechanism and certain of the drive mechanism for the reeling mechanism;

Fig. 14 is a plan view looking down on the traverse which is associated with the reeling 40 mechanism;

Fig. 15 is a view taken on substantially line 15—15 of Fig. 14;

Fig. 16 is an elevation of the traverse mechanism shown in Fig. 14;

Fig. 17 is a sectional view taken substantially on line 17—17 of Fig. 16;

Fig. 18 is a fragmental view illustrating the change gear drive relationship of the lower portion of Fig. 9;

Fig. 19 is a plan view of the mechanism shown in Fig. 18;

Figs. 20 to 24 are sectional details for the conveying of current in connection with the stop motion;

Fig. 25 is a diagrammatic view of the counter;

Fig. 26 is a wiring diagram showing the starting

and stopping of the motor for driving the mechanism.

In proceeding with this invention I arrange that the supply packages will not rotate or revolve about the center of the formed cable. Each supply package does rotate about its own axis as wire is drawn therefrom. Supply packages are mounted on a creel and the wire is drawn from the several packages through a hollow spindle where the wire is laid in helical form and at the same time twisted. I provide that a double twist will be placed in the cable of the several strands of wire by leading the several strands back upon themselves and revolving the radially extending portions of the cable as it extends outwardly from the hollow center, shaft, or spindle. In order to economize space I lead the laid cable upwardly and then downwardly and package the cable beneath the laying mechanism. Prior to packaging however I twist the cable up still more tightly to set the helical lay already put in while relaxing the cable after so twisted as it passes through a false twisting mechanism. The cable may then be caused to travel through a straightener to take out any kinks and is pulled through the various processing mechanisms by a hauling device which permits of heavy tension being placed upon the cable to draw it through the various processing parts but a relaxation of the cable on the other side of the hauler so that it may be reeled under a considerably relaxed tension. The reeling mechanism is performed by a surface drive and is traversed while at the same time a counter is provided that the amount of formed cable may be known.

The various parts of the machine as indicated in the above general description each enter into the processing of the wire for the advantageous results performed. Stop mechanism is also provided to quickly stop the machine should one of the strands break prior to being laid. The various parts of the machine will be taken up and described in more detail under their various headings.

Supply creel

With reference to the drawings the stationary frame of the machine is designated 25 (see Figs. 3 and 6) in which there is mounted a rotating spindle 26 supported by means of the ball bearing 27. A collar 28 (see Fig. 3) having a plate 29 secured thereto at the lower side and a disc 30 secured thereto at the upper side is mounted upon the spindle on shoulders 31 and 32 to rotate with the spindle. A recess 33 is formed in the collar 28 to receive a pulley 34 journaled upon a shaft 35, which pulley has its periphery tangent to the hollow bore 36 of the spindle to provide a lead for the cable out of the spindle. A bushing 37 (see Fig. 6) is rotatably mounted by means of ball bearings 38 and 39 resting upon shoulders 40 and 41 of the spindle and carries the creel supporting deck 42 which is fixed to the bushing and rest thereon. This is termed the main deck. The ball bearing 38 is held in the bushing by means of a plate 42', flanged as at 43, which fits into a recess 44 in a plate 45 secured by bolt 46 to the lower end of the bushing 37. The bushing 37 is provided with V belt grooves 47 and 48 for purposes which will hereinafter appear.

Equally spaced about the axis of the creel I have provided upstanding package spindles 50 (see Figs. 3 and 5) upon which a spool 51 having a brake drum 52 and containing a package of wire 53 is provided. This spool with its brake drum 52 may rotate to permit the wire 53 to be drawn

therefrom. An arcuate brake shoe 54 (see Fig. 5) is provided as at 56 while a threaded pin 57 is engaged by a spring 58 to draw the brake shoe against the brake drum 52. Adjustment of the spring tension may be provided by disengaging the spring and threaded pin 57 and relocating the pin in the brake shoe. The wing nut 59 on the upper end of the package spindle will retain the spool in position. I have illustrated six of these package spindles equally spaced about the creel, which assist in the formation of uniform cable by the laying of the various strands thereof. The number of packages may of course be varied.

A guide post 65 is located adjacent each supply package radially between the supply package spindle and the central axis of the creel. A suitable number of these posts (see Figs. 2 and 3) extend upwardly from the main deck of the creel 42 to support a raised deck 61 for the support of a package 62 of wire having the same spool and brake mechanism as heretofore mentioned in connection with the spools on the main deck. Outwardly of each supply package there is provided a pair of drums 66 and 67 (see Fig. 5) with a guide pulley 68 adjacent the drum 66 and a guide pulley 69 adjacent the drum 67. The wire 70 as it is lead from the supply package (see Fig. 4) extends about the guide post 65, then about the guide pulley 68, then several times about the drum 66 and 67, and thence upwardly over the guide pulley 69, and then through a guide into and down the center of the hollow spindle. By reason of this long extent of traverse of the wire between its leaving the supply package and entering the hollow spindle, should a break occur, it will be a very simple matter to locate the broken end and piece the same up without the necessity of fishing a lost end of the wire through the hollow spindle where maneuverability is difficult. Drums as just described are arranged for each of the packages, including the package on the upper deck 62 and guide pulleys which lead therefrom except that pulleys 69 and 69' are substituted for pulley 69 in the delivery of the wire from the drums of the upper deck. The strand designated 71 leads from the supply package on the upper deck, and serves as the core for the cable, the other strands being laid about it.

The drums and pulleys just described are mounted upon a bracket 73 (see Fig. 5) which is secured to the deck 42 and which bracket provides upstanding ears 74 with openings 75 for shafts to rotatably support the drums 66 and 67, while an upstanding ear 76 is provided having an opening 77 for the support of guide pulleys 68 and 69. This bracket also forms an anchor as at 78 for one end 79 of the spring 58. These brackets are interposed between the supply packages on the deck 42 for the guiding of the strand material.

At the center of the creel 42 there is a guide 80 (see Fig. 6) which consists of a body 81 recessed as at 82 to receive guide pulleys 83 which are each mounted to rotate on a shaft 84 located in the outwardly extending bosses 85 (see Fig. 7) of the body. There is one of these guide pulleys 83 for each supply package on the deck 42, there being six in number in the illustration herein which are spaced apart equally angularly about the body of the guide 80. This guide is supported upon the creel 42 by its base 86 and bolts 87 (see Fig. 6) passing therethrough while it has a hollow standard 88 having a bore 89, through which the strands are passed. A center guide designated 90 is grooved as at 91 (see Fig.

8) into which each of the various strands pass to be guided just prior to their being laid about the center strand 71 which passes down through the opening 92 in this center guide and about which the various equally spaced strands in the guide 91 are helically wound. The center guide 90 is pointed at its lower end 94 with a groove tip 95 for directing the various strands into bore 36 of the spindle. The helical strands being laid about the center strands at this tip 95.

At one point in the periphery of the disc 30 (see Figs. 2 and 3) the slot 100 is provided for the mounting of the guide pulley 101 rotatably upon a shaft 102. The cable 103 extends down over the pulley 34, thence out over the pulley 101 and upwardly as at 104 to extend over pulley 105 (see Fig. 1) at the upper center of the machine and thence downwardly at 106 over a fixed pulley 107.

The disc 30 rotates with the spindle 26 as above indicated as does also the plate 29. Shafts 110 and 111 (see Fig. 3) are rotatably mounted in the plate 29 and disc 30 at points equally distant from the center axis thereof. A bushing 112 is mounted in the casing 25 and is provided with V grooves 113 and 114. This bushing supports the bearing 27 above mentioned by means of the plate 115 secured by bolts 116 therethrough which forms a housing for the ball bearing 27. Pulleys 117 and 118 are at the opposite ends of the shaft 110 and pulleys 119 and 120 are at the opposite ends of shaft 111. These pulleys are located so that the V grooves in these pulleys will be opposite the V grooves in the bushings 37 and 112. A belt 121 engages the V groove 114 on the bushing 112 and the V groove in the pulley 117 while the belt 122 engages the V groove 48 in the bushing 37 and also the V groove in the pulley 118. Likewise a belt 123 engages the V groove 113 in the bushing 112 and the V groove in the pulley 119 while the V belt 124 engages the groove 47 in the bushing 37 and the V groove in this pulley 120. As the spindle rotates motion will be transmitted by each of these belts to their pulleys and through their shafts to the pulleys at the opposite end and from them to the creel. The pulleys at the opposite ends of the shafts are of the same diameter. Therefore the drive which is imparted to the pulleys by reason of the rotation of the spindle will impart to the creel by reason of its bushing 37 a drive in the opposite direction equal to the drive of the spindle. The bushing 112 is stationary. It drives the shaft 110 one revolution for each revolution of the disc 30 and the creel is driven with reference to the spindle one revolution for each revolution of the disc in the opposite direction. Consequently the creel is stationary or does not move with reference to the casing 25 except that there may be some possible creeping due to slip of the friction belts along their V pulleys. From the above it will appear that the creel floats on the spindle but the ratio of drive is such that the creel does not rotate with reference to the casing. Other means of holding the creel from turning which are equivalent to that just described are set forth in my copending applications Ser. Nos. 508,128, 508,129, 508,130, 508,131, 508,132.

This upper part of the mechanism just described is enclosed in the casing designated 125 having a door hinged at 126 consisting of lattice-work formation 127 so that the mechanism is protected during a major part of the running thereof. The casing is slotted as at 128 that the cable portion 106 may extend therethrough. A suit-

able top or cover 129 is provided over this casing as a part thereof which is removable.

False twister

5 As shown in Figure 3 a bracket 130 is fixed to the structure 25 and containing a cylindrical portion 131 with ball bearings 132 and 133 mounted at either end thereof to rotatably support the shaft 134 providing a substantial bearing therefor. This shaft is hollow or provided with a central bore 135 for the passage of the cable therethrough. On the upper end of this shaft there is mounted a cap 136 having a pulley 137 with a V groove 138 therein, while on the upper end 15 of this cap there are provided supports 139 and 140 for the drums 141 and 142 about which the cable may be wound in the form of a figure eight a sufficient number of times to obtain the desired grip thereon for rotation of the cable, after which the cable is lead downwardly through the bore 135 to a means for performing the next operation thereon. The pulley 137 is revolved so as to place additional twists in the cable. The rotation will be such as to put about one or two turns 20 additional in the cable between the grip thereon due to the figure eight lead of the wire as the cable leads to the drums 141 and 142. However, as the cable leads away from the drums 141 rotation will cause the twist to be taken out of the cable an amount equal to that which is put into the cable on the opposite side of the nip thereof. Accordingly, the effect of the mechanism is to place additional twist in on the feeding-in side but to take out this same amount of twist on the feeding out side of the nip of the cable and accordingly no resultant twist occurs. Although 25 no resultant twist occurs, a change in the wire does occur inasmuch as the additional twist put into the wire serves to set the strands in their helical formation and provides a stress free wire so far as tendency to untwist is concerned after it leaves this operation. Accordingly if the wire is cut the several strands do not tend to fly apart but remain in their laid helical relation.

Straightener

After passing from the false twisting apparatus the cable passes through a straightener designated generally 150 (Figs. 1 and 3) which consists of staggered rolls 151 and 152 between which the wire extends and is flexed back and forth so as to take any kinks out of the wire and assist in laying the strands in the desired form of the cable. The flexing occurs in right angular planes.

Wire feed mechanism

In order to draw the wire through the straightener, the false twister, and from the supply packages, drums 160 and 161 (see Fig. 13) are provided about which the cable extends several times as at 162. The tension on the cable leading to the drum 160 is very great while the number of turns about the drum provides sufficient friction not only for the drive or feed of the wire to this mechanism but is also sufficient to permit the wire to be taken off as at 164 with considerably less tension. The drum 161 is driven by suitable drive mechanism as will be hereinafter explained.

Reeling mechanism

The cable is packaged or reeled (see Fig. 13) upon the cylindrical barrel 170 of a suitable spool which may be removed from the machine and which is driven by a cork covered cylinder 171 supported on the arm 172 pivoted on a shaft 174

and held against the surface of the cylinder 170 by the weight 173 at the end of an arm 226 extending from shaft 174 in the opposite direction. The cable is led to this package over a guide pulley 175 which is moved axially of the package 5 by a traverse mechanism designated 176 as it engages the pulley from the guide 171 over which it leads from the feed mechanism above described.

The traverse mechanism (see Figs. 14 to 17) 10 consists of a pair of threaded shafts 178 and 179 and a guide shaft 180 along which the yoke member 181 may slide and also rock so that either of the nuts 182 and 183 may be engaged with one of the threaded shafts. The tube 184 carries the pulley 175 for the guiding of the cable 166 on to 15 the package 170. The yoke 181 has an upstanding arm 185 which as it moves near the end of its stroke will engage the fin 186 held by arm 187 in adjusted position along the rod 188, while the arm 189 pressed by spring 190 tends to move the 20 arm 185 so as to rock the yoke 181. After the arm 185 of the yoke has traveled so as to pass beyond the fin 186 the arm 189 will snap the yoke 185 over and disengage the nut 182 and cause engagement of the nut 183 with the threaded 25 shaft 178. The arm 185 will then travel in the opposite direction along the opposite side of the fin 186 and will first engage the fin 191 and will then engage the arm 192 which by reason of spring 193 will press the arm 185 in the opposite direction or to the right in Fig. 17 as the arm slides along fin 191 until the arm 185 passes beyond the extent of the fin 191 when this arm 192 will then snap the yoke in the opposite direction 30 so as to disengage the nut 183 from the threads 178 and again engage the nut 182 with the shaft 179 that the yoke may reverse its direction. The traverse mechanism will thus reverse itself for the reciprocation of the pulley back and forth to the axial extent of the package to be formed.

The drive for the various parts

The main driving motor (see Fig. 9) is designated 200 and is provided with an armature shaft 201 carrying a pulley 202 over which three V belts 203 extend to engage the pulley 204 having three cooperating grooves for the three belts 203 whereby a direct drive is provided for the spindle 26 to drive or rotate the flywheel 30 which revolves the cable about the hollow spindle. The mechanism for maintaining the creel stationary while the spindle is driven by means of the shafts 110 and 111 has been explained.

At the lower end of the spindle 26 a worm 205 (see Fig. 3) is provided which drives the worm wheel 206 which in turn drives through shaft 207 the gear 208 and in turn this gear drives the gear 209 (see Figs. 9, 18, and 19) through the change gear 210 mounted upon the swinging arm 211 and having a slot 212 through which the binding means 213 passes to hold the arm in a position to cause the change gear 210 to engage the gears 208 and 209 to transmit motion from one to the other. The gear 209 is mounted on the shaft 214 upon which the drum 161 is mounted and by means of which the same is rotated. The work which embraces the drums 160 and 161 causes rotation of the drum 160.

The drive for the packaging mechanism is taken from the driven drum 160 of the feeding mechanism (see Figs. 18 and 19). The drum 160 is mounted upon a shaft 220 which also carries a V-pulley 221 which is of the split type having a spring 222 to urge the two parts together. The

distance that the belt extends into this pulley will determine the circumference which is effective to turn the belt. This belt 221 (see Fig. 13) is trained over a fixed pulley 223 mounted as at 224 and thence about a second pulley 225 on shaft 174, and then extends about a pulley 228 on a shaft 229 carried by an arm 230, which arm is pivoted to swing about the pivot 231. This arm may be swung about the pivot 231 to draw the belt into or permit it to extend to a greater diameter of the pulley 221. Such swinging is effected by the bolt 232 passing through the boss 233 and adjusted by a head 234 through the abutment engaging the boss.

The shaft 174 has a pulley 240 about which a belt indicated at 241 extends to drive a pulley 242 on shaft 243 at the end of arm 172 upon which the cork drum 171 is provided so as to rotate this driving drum at a constant speed which is in surface contact with the packaging drum 170 so as to reel the cable thereon.

The drive for the traverse is taken from shaft 250 (see Fig. 14) upon which the take-up package is mounted. The shaft is equipped with a Reeves drive pulley having halves, the movable half 252 being urged by spring 253 toward the fixed half 251. A belt 254 engages the separable pulley and also a pulley 255 which drives the gear 259 (see Fig. 16) and in turn the gears 260 and 261, which mesh with each other, one being on the end of threaded shaft 178 and the other on the end of threaded shaft 179 to drive the same. Shaft 179 also carries gear 256 meshing with gear 257 on the shaft 180 which carries the pulley 175.

The drive for the false twisting mechanism shown in Figs. 10 to 12 is taken from the shaft 26 upon which is a pulley 265 which operates a belt 266 in turn rotating the pulley 267, which 40 is carried by an arm 268 pivoted as at 269 about a pin 270 supported in the bracket 271. A bracket 271' pivotally mounts an arm 272 which carries a pulley 273 urged into engagement with the belt 266 by a spring 274, the arm 272 being pivoted as at 275. A shaft 276 is driven by the pulley 267 and this shaft carries a Reeves drive pulley 277 having a spring 278 to urge the two halves of the pulley together. A belt 279 extends about the pulley 277 and also extends about pulley 137 of the false twister device. The drive 45 may be changed by drawing the belt 279 further into or letting it out to a larger diameter of pulley 277. In order to adjust the position of the belt 279 in pulley 277 the pivoted arm 268 carries a swivelly mounted nut 280 which may be moved by a threaded shaft 281 having a handle 282 extending through the casing 283 so as to swing the arm 268 about its pivot 270 to vary the position of the belt 279 in the pulley 277. Thus the relative speed of the false twister 50 mechanism may be adjusted. As the swinging of the arm 268 occurs the pulley 273 will be moved by a spring 274 to take up any slack which might occur in the belt 266.

A motor control mechanism (see Fig. 9) designated 288 is driven from the spindle 26 by pulley 285 through belt 286 engaging pulley 287 which is so connected into the field of the motor which drives the spindle so that when the 55 stop mechanism is operated to stop the machine the field of the motor is reversed so that electrically a force is acting to turn the motor in the opposite direction to bring the spindle to a stop more quickly. This mechanism so operates that 60 when the spindle slows down beyond a certain

predetermined number of revolutions per minute the switch which causes a reversal of the field is thrown out and the spindle is permitted to come to rest.

Strand breakage stop motion

In order to control the operation of the machine an electrical stop motion is provided. The machine is arranged to stop upon the breaking of one of the strands of the creel supply packages by the arrangement shown more particularly in my copending application Serial No. 508,133 and shown herein at Figs. 2, 5, and 20 to 24 inclusive.

Each of the guide posts 65 (see Fig. 20) consists of a solid upstanding member 290 which is threaded as at 291 into the creel support 42. A bearing 292 is provided on this member 290 and a similar bearing is provided near the upper end of the member, and a sleeve 293 is rotatably supported on these bearings which may freely rotate as the strand designated 70 is drawn about this guide post. A collar or circuit closing member 294 is slidably related to the sleeve 293 and will move by gravity to the lower part of the sleeve when free to do so. This collar has an outwardly rounded flange 295 to rest upon the strand material 70 so as to be supported thereby and prevented from gravitating to its lower position so long as the strand material extends about the post. However, when this strand material breaks the collar will slide to its lowermost position.

An annular electrical contact strip 296 is supported by insulation 297 from the creel 42 and is provided with openings 298 sufficient so as to place the contact strip from each of the guide posts which extend therethrough. An electrical connection may be made between the strip 296 and post by the collar when in its lowermost position.

The flange of the creel is equipped with a boss 299 having a bore 300 (see Fig. 24) in which the insulating sleeve 301 is mounted. This sleeve carries a brush 302 pressed by the spring 303 which may be adjusted by the threaded rod 304 so that the desired pressure may be obtained and which rod is held in position by threadingly engaging a part of the bushing. Electrical connection is established between the brush 76 and the annular contact 296 by a strip 305 secured as at 306 to the member 296 and by nut 307 to the threaded rod 304 to establish electrical connection between them.

The brush 302 engages an annular contact member 308 which is insulated as at 309 from the disk 30 but so located that as the disk revolves this annular member will be engaged by the brush 302 at all times. An annular member 310 carried on the under side of the disk 29 (see Fig. 23) and insulated therefrom is electrically connected to the annular member 308 by a strap 311 secured to these members by bolts 312 and 313 through insulating bushings 314 in both of said disks such as by means of nuts 315.

The framework 25 is also equipped with a boss 316 (see Figs. 2 and 22) having a bore 317 with insulating bushings 318 therein which holds a threaded member 319 to adjustably engage the spring 320 which urges the brush 321 against the annular contact member 310. A certain terminal arrangement by nuts 322 and 323 enable the circuit lead 324 to be secured thereto.

The package on the upper disk is similarly supplied through post 68' (see Fig. 21) with a con-

tact 325 insulated as at 326 and connected to the annular contact 296 by the bus bar or lead 327.

Counter

5 A counter 330 (see Figs. 1 and 25) is provided to indicate the length of cable which has passed through the machine and to stop the machine upon a predetermined length having been furnished. The counter is driven by a worm gear 331 on shaft 220. A worm 332 engages the worm and rotates shaft 333 (see Fig. 25) to drive gear 334 which in turn drives gear 335. A mutilated gear 336 has a tooth which turns the member 337 one tooth each revolution to revolve shaft 338. This shaft in turn has a mutilated gear 339 to turn member 340 one tooth each time it revolves and each of these parts serve to rotate certain indicating wheels to record the length produced. Gear 340 rotates shaft 341 which carries a contact 342 to engage contact 343 to close a circuit and cause stopping of the machine.

Wiring circuit

The drive motor 200 is so controlled that it may be jogged on and off in starting by electrical controls or it may be operated forward or reverse. Also the motor may be stopped upon opening of the doors 127 which control a guard switch, by the counter arriving at a predetermined count or by the drop wire arrangement of Fig. 20 when a wire strand breaks. Likewise a so-called plug-in switch which operates to reverse the motor field is provided. The circuit including all of this arrangement is shown in Fig. 26 which will show the electrical control provided.

To start the machine by motor 200 all switches and thermal overloads must be properly set and the selector switch properly set for the desired directional rotation of the motor. Assuming the selector switch has been set for a so-called forward rotation of the motor on the run position, then by the starter button 350 the initial circuit will be closed through which relay 1 is energized. This circuit includes the line 351 extending from the transformer 349 through terminal C-3, stop button contacts, starter button contacts 352-353, terminal C-1, coil 354 of relay 1, terminal G-1, guard switch, terminal P-2, counter switch, terminal P-1 and thence by line 355 to contact of transformer. Energizing of coil 354 of relay 1 will close the sets of contacts 356 and 357 thereof. The circuit to the magnet coil of the forward switch includes the line 351 extending from the transformer through terminal C-3, stop button contacts, line 358 to terminal C-4, overload 359 and 360, line 361, bridged contacts 357 of relay 1, terminal C-2, bridged contacts 362 of forward position of selector switch, line 363, terminal F-1, line 364, coil 365 of forward switch, line 366, closed contacts 367 of reverse switch, terminal P-1 and by line 355 to transformer. Energizing of coil 365 of forward switch will move mechanism to close sets of contacts 368, 369, 370, 371 and open contacts 372. This will close the lines extending from terminal L1-L2 and L3 to terminal T-1, T-2, and T-3 through contacts 370, 369, and 368 respectively. Rotation of motor in the forward direction will actuate the plugging switch to bridge the contacts 372-373 or 373' thereof.

Upon energizing of relay 1 and actuating of the forward switch a second circuit to coil 354 of relay 1 will be established and the starter button may be released to open the line therefrom to terminal C-1. This second circuit includes the line 351 extending from transformer 349 through

terminal C—3, stop button contacts, contact 353 of starter button, bridged contacts 374 of jog run switch, terminal J—1, contacts 356 of relay 1, line 375, contacts 371 of forward switch, line 376, closed contacts 377 in relay 2, line 378 through 5 coil 354, line 379, terminal G—1, guard switch, terminal P—2, counter switch, terminal P—1 and line 355 to contact of transformer 349.

Upon the bridging of the drop wire contacts by 10 294 a circuit is established to energize relay 2 and open the circuits to relay 1 and to coil 365 of the forward switch which stops the motor. The circuit energizing relay 2 includes the line extending from the ground 380 of the transformer, line 380' from P—1, from ground 381 through bridged contacts of drop wire, line 382, coil 383 of relay 2, line 384, contacts 351 of relay 1, line 364, overloads 360, 359, line 385 to terminal C—4, stop button contacts, terminal C—3 and line 351 to transformer 349. Energizing the coil 20 of relay 2 will open contacts 377 of relay 2 and stop flow of current through coil 354 of relay 1. This will de-energize relay 1 and open circuits at contacts 356—357. This action will de-energize coil 365 in the circuit now opened at contacts 357. Mechanism of the forward switch will now be actuated to open contacts 368, 369, 370, and 371 and close contacts 372 to establish a closed circuit for the coil of the reversing switch. This latter circuit includes the line 385 from the transformer, terminal P—1, contacts 372 of forward switch, coil 386 of reversing switch, line 387, terminal R—2, contacts 378—372 of plugging switch, line 388, terminal N, terminal J—2, contacts 389, bridge 390 of jog run, line 391, contact 353 of starter button, bridge 392, contacts of stop button, terminal C—3 and line 351 back to transformer 349. Contacts 393, 394, 395, 396 will be closed and contacts 397 opened when the reversing switch coil is energized. Lines L—1, L—2 and L—3 will now extend through the closed contacts 393, 394, 395 of reversing switch and from there to terminals T—3, T—2 and T—1 to motor. The rotation of the motor will now be in the reverse direction which will actuate the plugging switch to open contacts 372—373 and open the circuit to the reverse switch coil 386, de-energizing the same and permitting the mechanism of this switch to open contacts 393, 394, 395, and 396 thereof to open lines L—1, L—2, and L—3 and bring the motor to rest.

The second circuit for coil 354 of relay 1 will be similar to the second circuit established as previously stated when the forward switch is actuated with the exception that the circuit will be closed through contacts 396 of the reversing switch. These two contacts are connected in parallel to now open contacts 371 of forward switch.

If the drop wire contacts are now bridged a 60 circuit is established to energize relay 2 to open contacts 377 in the second circuit of coil 354 of relay 1. De-energizing relay 1 will open contacts 351 of relay 1 in which circuit the coil of reversing switch is located. This will de-energize the reverse switch coil and permit opening of contacts 393, 394, 395, 396, and close contacts 397. The flow of current from lines L—1, L—2 and L—3 to the motor 200 will now be interrupted. A closed circuit will be established for coil 365 of forward switch through closed contacts 397 and contacts 372—373' kept closed by the momentum of motion of motor. This circuit will include line 351 extending from transformer 349 through line 351, terminal C—3, contacts of stop

button, contact 353 of starter button 374, 390 and 388 of job run, line 398, terminal J—2, line 388, terminal N, contacts 372, 373' of plugging switch, terminal F—2, line 399, terminal F—1, coil 365 of forward switch, closed contacts 397 of reversing switch, terminal P—1 and to ground or left contact of transformer.

The energized coil 365 will actuate the forward switch mechanism to close the circuits of lines S—1, S—2, and S—3 through contacts 368, 369, 370. The motor will now be set into motion in the opposite direction and provide a similar reversal of the plugging switch.

If it be assumed that the selector switch has 15 been set for the so-called reverse direction, pressing of the starter button will establish the same initial circuit to energize relay 1 as if the selector switch were set for forward rotation as previously described, that is from transformer, terminal C—3, stop button contacts, starter button contact 352, 353, line 400, terminal C—1, line 401, coil 354 of relay 1, line 379, terminal G—1, guard switch, terminal P—2, counter switch, terminal P—1 and by line 355 to transformer. When the 20 selector switch is set to reverse position the contacts 403 are bridged. In this situation no current can flow to coil 365 of forward switch because contacts 362 in selector switch are open and line from coil 365 through F—1 is opened at 25 plugging switch prior to rotation of motor. Upon energizing of relay 1 a circuit is closed to energize the coil 386 of reversing switch. This circuit includes line 351 extending from transformer through terminal C—3, stop button contacts, line 358, terminal C—4, contacts 357 of relay 1, line 404, terminal C—2, line 405, contacts 403 of selector switch, line 406, terminal R—1, line 407, terminal R—2, line 387, coil of reversing switch, contacts 372 of forward switch, terminal P—1 30 and to ground or by line 355 to transformer. Energizing the coil of the reverse switch will 35 actuate the mechanism to open contacts 397 and close contacts 393, 394, 395, and 396. This will 40 close the lines L—1, L—2, and L—3 to motor in the manner previously described and set the motor in motion in the so-called reverse direction. The plugging switch will be actuated by rotation of the motor to close contacts 372—373', which 45 will open contacts 372—373' and interrupt the flow of current to coil 365. This will permit the forward switch mechanism to open contacts 368, 369 and 370 and open the lines of current to motor.

The initial circuit to relay 1 as well as the 50 second circuit established for maintaining relay 1 in energized condition each include the counter switch and guard switch. Should either of these switches be opened the flow of current to relay 1 will be interrupted and the motor stopped.

All circuits also extend through contacts of stop button switch and to deenergize the circuit it is merely necessary to press the stop button.

The jog run includes two sets of contacts 374 and 389. Contacts 374 may be electrically connected. On the jog run the switch is set to have contacts 374 open. The second circuit established for relay 1 includes contacts 374. If these are set to be in open condition no second circuit is established and releasing of the starter button 65 will bring the motor to rest.

The circuit to relay 2 can only be established through ground extending through the drop wire 70 294. Consequently opening of counter and/or guard switch will not set any circuit in motion to reverse rotation of motor. Therefore only closing 75

ing of the drop wire circuit will cause a reversal of motor direction.

I claim:

1. In a wire cable machine, a creel carrying a plurality of supply packages of wire strands, a hollow spindle through which the strands extend, means for twisting and laying the strands helically, means to false twist the laid strands in the same direction to set the helical lay of the strands in the formed cable, means to oppositely flex the cable to remove kinks therefrom, means to engage and feed the cable through said means, a measuring device associated with the last said means and driven thereby, and means to reel the cable.
2. In a wire cable machine, a creel carrying a plurality of supply packages of wire strands, a hollow spindle through which the strands extend, means for twisting and laying the strands helically, means to false twist the laid strands in the same direction to set the helical lay of the strands in the formed cable, means to oppositely flex the cable to remove kinks therefrom, a pair of drums about which the cable is wound a plurality of times and means to drive one of the drums to feed the cable through said means, a measuring device associated with said drums and means to reel the cable.
3. In a wire cable machine, a creel carrying a plurality of supply packages of wire strands, a hollow spindle through which the strands extend, means for twisting and laying the strands helically, means to false twist the laid strands in the same direction to set the helical lay of the strands in the formed cable, and means driven from the spindle to reel the cable, and means to count the length of cable made.
4. In a wire cable machine, a creel carrying a plurality of supply packages of wire strands, a hollow spindle through which the strands extend, means for directing the cable radially outwardly of the spindle and then in the opposite direction, means for rotating the spindle and the radially extending portion to place in the strands a double twist and lay the strands helically, means to false twist the laid strands in the same direction to set the helical lay of the strands in the formed cable, and means driven from said spindle to reel the cable.
5. In a wire cable machine, a creel carrying a plurality of supply packages of wire strands, a brake for retarding the rotation of each of said packages, a hollow spindle through which the strands extend, means for driving said spindle, means for twisting and laying the strands helically, means to false twist the laid strands in the same direction to set the helical lay of the strands in the formed cable, and means driven from said spindle to reel the cable.
6. In a wire cable machine, a creel carrying a plurality of supply packages of wire strands, a plurality of guides about which the wire strands from each package extends to change its direction, a hollow spindle through which the strands extend, means for driving said spindle, means for twisting and laying the strands helically, means to false twist the laid strands in the same direction to set the helical lay of the strands in the formed cable, and means driven from said spindle to reel the cable.
7. In a wire cable machine, a creel carrying a plurality of supply packages of wire strands, a vertically disposed hollow spindle extending through said creel and rotatable relative thereto, and through which the strands extend, means for
- 5 rotating the spindle, means for revolving said strands about said creel for twisting and laying the strands helically, means driven by said spindle to false twist the laid strands in the same direction to set the helical lay of the strands in the formed cable, means driven by said spindle to engage and feed the cable through said means, and means to reel the cable.
- 10 8. In a wire cable machine, a creel carrying a plurality of supply packages of wire strands, a hollow spindle through which the strands extend, means for rotating said spindle, a disk carried by and rotatable with said spindle and extending at right angles to its axis and with a rotating guide at its periphery, means to direct the strands from through the spindle radially outwardly of the disk and over said rotating guide, a guide positioned above said creel and over which said strands extend from said rotating guide for revolving said
- 15 20 strands about said creel to double twist and lay the strands helically, means to false twist the laid strands in the same direction to set the helical lay of the strands in the formed cable, and means driven from said spindle to reel the cable.
- 25 9. In a wire cable machine, a vertically disposed hollow spindle, means for rotating the spindle, a creel rotatably supported wholly on said spindle and carrying a plurality of supply packages of wire strands, means for driving the creel from the spindle in the opposite direction from the spindle a number of revolutions equal to the rotation of the spindle, means for directing the wires from the supply packages through the hollow spindle, means for guiding and revolving the wires about said spindle and creel for twisting and laying the strands helically, means to false twist the laid strands in the same direction to set the helical lay of the strands in the formed cable, and means driven from said spindle to feed the cable through said last said means to reel the cable.
- 30 40 10. In a wire cable machine, a vertically disposed hollow spindle, means for rotating the spindle, a creel rotatably supported wholly on said spindle and carrying a plurality of supply packages of wire strands, means for driving the creel from the spindle in the opposite direction from the spindle a number of revolutions equal to the rotations of the spindle, means for directing the wires from the supply packages through the hollow spindle, a disk carried by and rotatable with said spindle and extending at right angles to its axis with its periphery extending beyond the outer edge of said creel, a rotating guide at its periphery, means to direct the wires from through the spindle radially outwardly of the disk and over said rotating guide, a guide positioned at a location above said spindle and over which the wires extend from said rotating guide to revolve the wires about said creel to double twist and lay the strands helically, means to false twist the laid strands in the same direction to set the helical lay of the strands in the formed cable, and means driven from said spindle to feed the cable through the last said means.
- 45 55 60 65 70 75 11. In a wire cable machine, a creel comprising a deck carrying a plurality of packages of wire strands, a vertically disposed hollow spindle extending through said creel and rotatable relative thereto, means for driving said spindle, an additional package of wire strand serving as a core, and supported on said creel above said spindle, means for directing all of the strands through means for twisting and laying the other strands helically about said core, means to false twist the laid strands in the same direction to set the helical

lay of the strands in the formed cable, and means driven from said spindle to reel the cable.

12. In a wire cable machine, a creel comprising a deck carrying a plurality of packages of wire strands and an additional package of wire strand above the other packages, a brake for retarding the rotation of each of said packages, a vertically disposed hollow spindle extending through said creel and rotatable relative thereto, means to rotate said spindle, an additional package of wire strand serving as a core, means for directing all of the strands through said spindle, means for twisting and laying the other strands helically about said core, means to false twist the laid strands in the same direction to set the helical lay of the strands in the formed cable, and means driven from the spindle to reel the cable.

13. In a wire cable machine, a creel carrying a plurality of supply packages of wire strands, a hollow spindle through which the strands extend, means for rotating said spindle, means for twisting and laying the strands helically, means to false twist the laid strands in the same direction to set the helical lay of the strands in the formed cable comprising a tube driven from said spindle and through which the cable extends, means to grip the wire cable and revolve the same about its axis, and means driven from said spindle to reel the cable.

14. In a wire cable machine, a creel carrying a plurality of supply packages of wire strands, a hollow spindle through which the strands extend, means for rotating said spindle, means for twisting and laying the strands helically, means to false twist the laid strands in the same direction to set the helical lay of the strands in the formed cable comprising a rotatable tube, a pair of pul-

leys carried by the tube over which the cable is trained sufficiently to gain a bite upon the cable and revolve the same about its axis, said tube being driven from said spindle.

15. In a wire cable machine, a creel carrying a plurality of supply packages of wire strands, a hollow spindle through which the strands extend, means for rotating said spindle, means for twisting and laying the strands helically, means driven from said spindle to false twist the laid strands in the same direction to set the helical lay of the strands in the formed cable comprising a tube, a pair of pulleys carried by the tube over which the cable is trained in the form of a figure eight sufficiently to gain a bite upon the cable and revolve the same about its axis, said tube being driven from said spindle.

16. In a wire cable machine, a creel carrying a plurality of supply packages of wire strands, a hollow spindle through which the strands extend, means for rotating said spindle, means for twisting and laying the strands helically, means to false twist the laid strands in the same direction to set the helical lay of the strands in the formed cable, and means driven from said spindle to reel the cable, and means to count the length of cable made.

17. In a wire cable machine, a creel carrying a plurality of supply packages of wire strands, a hollow spindle through which the strands extend, means for rotating the spindle, means for twisting and laying the strands helically, means driven from said spindle to false twist the laid strands in the same direction to set the helical lay of the strands in the formed cable, and means driven from the spindle to reel the cable.

ALBERT E. WINSLOW.
